UNITED STATES PATENT OFFICE.

EARL A. SARGENT, OF RAMSEY, NEW JERSEY.

VALVE-GRINDER.

1,201,354.

Specification of Letters Patent.

Patented Oct. 17, 1916.

Application filed December 7, 1915. Serial No. 65,587.

To all whom it may concern:

Be it known that I, EARL A. SARGENT, a citizen of the United States of America, residing at Ramsey, in the county of Bergen and State of New Jersey, have invented new and useful Improvements in Valve-Grinders, of which the following is a specification.

This invention relates to valve grinding devices and has for its principal object the provision of a device of this character which may be manually adjusted to its work in an expeditious manner and one which will include an oscillating tool and a driving motor therefor, the latter being positioned relatively of said tool, whereby the weight of the motor may be centralized relatively of the tool with a resultant uniform retention of the tool against the valve during the grinding operation.

A still further object of the invention resides in the construction of a valve grinding device which will include a motor and an oscillating tool and power transmitting mechanism between the former and the latter and associated therewith so that the entire structure will possess a high degree of efficiency, simplicity, durability and compactness.

30 A still further object of the invention resides in the provision of an actuating tool, means forming a bearing therefor, and devices adjustable relatively of the bearing and designed whereby they may be extended 35 into the valve chamber and associated with the walls thereof, so as to center the bearing in the chamber and in turn, operate to invite an alined relation of the tool to the valve.

40 Other objects and advantages will be presented as the nature of the invention is better understood.

In the drawings forming a part of this specification and in which like reference numerals indicate similar parts throughout the several views: Figure 1 is a vertical section through the device showing parts in full lines. Fig. 2 is a horizontal section taken on the line 2—2 of Fig. 1. Fig. 3 is 50 a bottom plan view of the device showing the centering members.

With a view to providing a valve grinding device of a portable character which may be conveniently lifted manually from place to place about the engine and readily

associated with the valve so as to set up therein and quick oscillatory movements, it is preferred that a casing 1 be employed and as illustrated, said casing is provided with a base or crown wall 2 having a depending bearing 3 which is adapted into the valve chamber as clearly illustrated in Fig. 1. This casing is provided with a cross bar 4 to which the base of a motor 5 is secured. At this moment it is stated that the motor 65 is superposed relatively of the bearing 3 so that its weight may be used as a means for uniformly maintaining a coupled association of the actuating tool with the valve during the grinding operation. The upper 70 crown 6 of the casing is provided with a suitable handle whereby the device can be conveniently moved manually from place to place as the occasion demands or necessitates. Located between the crown tool and 75 said bar 4, of the casing is a bar 8. The grinding tool 9 is provided with a shank which is free to oscillate in the bearing 3 and in said bar 8. The lower end of said tool is in the form of a flat head 10 which is 80 adapted to be inserted in the usual kerf in the valve as shown in the dotted lines in Fig. 1. This tool terminates at its opposite end above the bar 8 and it fixedly supports a crank arm 11.

The power of transmitting mechanism consists of a bevel pinion 12 upon the shaft 13 of the motor 5, said pinion meshing with a similar pinion 14 upon a driven shaft 15. This shaft has its lower end journaled in the bars 4 and 8 while its upper end is journaled in a horizontal bearing 16 which extends from one side of the casing. The mentioned shaft 15 carries a gear wheel 17 which meshes with the teeth arranged about 85 the periphery of a crank wheel 19 and supported from a bearing upon the bar 8. The wheel 18 carries a wrist pin 20 to which one end of a pitman 21 is connected, the opposite end of said pitman having operative 90 connection with the crank arm 11. In this manner it is observed that power from the driving shaft 5 will be transmitted to the driven shaft 15 and in turn, said power will be carried to the wheel 18 so as to set up 95 rapid reciprocatory movements in the pitman 21 and continuous oscillatory movements in the grinding tool as will be understood. The valve is then operated in a like manner 100 against the seat and inequalities in the 105 110

seating surfaces of the valve and the valve seat and carbon accumulations are satisfactorily removed.

The crown wall 2 of the structure is provided, respectively at the opposite side of the bearing 3 with centering members, each having an attaching flange 22 and a depending arcuate flange 23, the latter being concentric with the bearing 3 and designed so that their convex surfaces 24 are adapted to come against the next adjacent walls of the valve chamber. The attaching flange 22 of each of said centering members is provided with a longitudinal slot 24. Screws 26 pass through said slot and into the crown 2. It is evident, through the described formation that the centering devices may accommodate themselves to the internal diameter of a valve chamber of a known size, causing the bearing 3 to be centered in the chamber and insuring against lateral derangement of the grinding tool from the kerf of the valve. This last named feature, when combined with the precise location of the motor 5 combines therewith to invite a satisfactory operation of the tool at all times. The handle 7 is located in line with the grinding tool 9 and slight pressure of the hand may be readily applied thereto for the purpose of preventing vertical derangement of the grinding tool from the valve.

The motor 5 which is conventionally shown herein is of the electric type and the lead wires thereof may be extended to any

well known electric source. The electric circuit may be controlled by a suitable press piece or button 28 mounted upon the casing 1 in sufficient proximity to the handle 7 so as to permit convenient manipulation thereof at the requisite time. It is desired also to mention that the screws 25 of one of the centering devices are disposed in the same horizontal line with the screws on the companion centering member whereby both members will be concentrically related to the bearing 3 at all times.

What is claimed as new is:—

A valve grinder comprising, a tool, a casing having a depending bearing receiving the tool therethrough, driving means for the tool, and centering members adjustably mounted at the base of said casing, respectively at opposite sides of said bearing, said centering members being adapted to be inserted in the valve chamber and engaging against the walls thereof to hold the tool against lateral displacement from the valve, the said tool driving means comprising a motor located above the tool in axial alignment therewith and serving to hold the tool against undue vertical displacement from the valve.

In testimony whereof I, affix my signature in presence of two witnesses.

EARL A. SARGENT.
